UNITED STATES PATENT OFFICE.

CARL W. F. STROBEL, OF LIMA, OHIO.

RAILROAD-CROSSING SIGNAL.

1,328,854.

Specification of Letters Patent. Patented Jan. 27, 1920.

Application filed February 21, 1918. Serial No. 218,475.

To all whom it may concern:

Be it known that I, CARL W. F. STROBEL, a citizen of the United States, residing at Lima, in the county of Allen, State of Ohio, 5 have invented a new and useful Railroad-Crossing Signal; and I do hereby declare the following to be a full, clear, and exact description of the invention, such as will enable others skilled in the art to which it 10 appertains to make and use the same.

The present invention relates to a railroad crossing signal, and has for its object to provide a device of this character which embodies novel features of construction where- 15 by a train approaching from either direction will automatically cause an alarm to be sounded, said alarm continuing to sound while the train is passing the crossing and being automatically cut off after the train 20 has proceeded to a point beyond the crossing.

Further objects of the invention are to provide a crossing signal of this character which is dependable in its operation, which 25 can be installed upon any railroad track and arranged to be actuated by the usual rolling stock, and which is entirely automatic in its operation.

With these and other objects in view, the 30 invention consists in certain novel combinations and arrangements of the parts as will more fully appear as the description proceeds, the novel features thereof being pointed out in the appended claims.

For a full understanding of the invention, reference is to be had to the following 35 description and accompanying drawings, in which:—

Figure 1 is a top plan view of a railroad 40 crossing provided with a signal constructed in accordance with the invention, portions being broken away.

Fig. 2 is a longitudinal sectional view 45 through the same.

Fig. 3 is an enlarged sectional view 50 through the trip actuated switch boxes which are mounted upon the track at opposite sides of the crossing, the electric wiring for the crossing signal being shown dia- grammatically.

Fig. 4 is a transverse sectional view 55 through one of the switch boxes.

Corresponding and like parts are referred to in the following description and indicated in all the views of the drawings by the same reference characters.

Referring to the drawings, which illustrate one embodiment of the invention, the reference character A designates a railroad track which is of the conventional construc- 60 tion, and B a crossing. A signal post 1 is arranged in a convenient position at the crossing and a signal such as the electric bell 2 mounted thereon. Switch boxes E and F which are similar in construction are 65 mounted upon the track A at opposite sides of the crossing, said boxes containing train actuated switch means for automatically sounding the bell or alarm 2 upon the approach of a train and stopping the bell after 70 the train has passed the crossing.

The switch boxes E and F may be conveniently mounted between adjacent pairs of railroad ties, being shown in the present instance as each provided with end flanges 75 3 which rest upon and are secured to the ties. A removable cover 4 closes the top of each of the boxes E and F, said cover being longitudinally slotted to receive the upper end of an upright trip lever 5 which projects 80 above the box and may be bent laterally at 5^a so as to project into the path of the wheels of the rolling stock and be engaged thereby. The trip lever 5 is provided at an intermediate point in its length with a 85 ball 6 which is loosely seated in a suitable socket provided by notches 7 in the upper edges of a pair of transversely extending and upwardly converging walls 8. A weight 9 is applied to the lower end of the 90 trip lever 5 and normally holds the same in an upright position, although it is free to swing laterally in either direction. The upwardly converging walls or uprights 8 are flanged at their lower ends, as indicated at 95 8^a, so that they can be secured to the bottom of the switch box, and the upper edges of the walls are spaced from each other so that the lever can be readily inserted in position when the removable side plate 10 at 100 one side of the box is displaced.

A pair of arms 11 project laterally from opposite sides of each of the trip levers 5, being shown as inclined downwardly therefrom. These arms 11 terminate over the 105 upper ends of, and are intended to actuate the respective plungers 12 and 13 of switches which are mounted within the box upon opposite sides of the upright lever. These plungers are slidably mounted within 110 brackets or guide arms 14, being arranged for vertical movement, and being normally

held in an elevated position by springs 15. Contacts 16 and 17 are arranged under the respective plungers 12 and 13 so as to be engaged thereby to close electric circuits 5 when the plungers are moved downwardly against the action of the springs 15. These contacts 16 and 17 may be supported in any suitable manner, as upon the brackets 18, being properly insulated so that the electric 10 circuits will not close until the plungers are actuated. With this construction it will be obvious that when the trip lever 5 is moved in one direction the plunger 12 will be moved downwardly into engagement with the contact 16, while when the trip lever 15 is moved in the opposite direction the plunger 13 will be moved downwardly into engagement with the contact 17.

By reference to Fig. 3 it will be observed 20 that the plungers 12 and 13 are reversely arranged within the two switch boxes E and F, although in all other respects the switch mechanism within the two boxes is identical in construction. The plungers 12 are mounted to return to their original positions and open the circuits controlled thereby as soon as released by the trip levers 5. On the contrary, the plungers 13 are adapted to be held in operative position by detents 19 until 25 electro-magnets 20 are energized and caused to swing the detents away from the plungers. The electro-magnet 20 of each of the switch boxes E and F is interposed in an electric circuit which is controlled by the plunger 12 of the opposite switch box. A train approaching the crossing from either direction will operate the trip lever 5 of the switch box on that side of the crossing, thereby moving the plunger 13 into engagement 30 with the contact 17 and closing the circuit which rings the bell 2. The detent 19, which is weighted at its lower end, as indicated at 19a, will automatically swing into engagement with a notch 21 in the plunger 13 and lock the plunger in operative position. As soon as the plunger is thus locked in operative position by the detent 19 the circuit will remain closed and the bell 2 continue to ring. After the train has passed 35 to the other side of the crossing it will engage the trip lever 5 of the other switch box and operate the same to move the plunger 12 of the said other switch box into engagement with the contact 16, thereby closing the circuit of the electro-magnet 20 of the first switch box. As soon as this electro-magnet is energized it will attract the detent 19 and 40 disengage the same from the plunger 13 of the first switch box, thereby permitting the plunger to be moved upwardly into its original position by the action of the spring 15. This opens the circuit of the bell 2 so that the bell is automatically stopped after the train has proceeded beyond the crossing.

65 One manner in which the crossing signal

may be wired is indicated diagrammatically by Fig. 3. The main feed wires 22 and 23 may receive current from any suitable source such as that indicated at 24. The wire 23 leads to the plunger 13 of the switch box 70 F. From the contact 17 of said plunger 13 a wire 25 leads to one of the terminals of the bell 2. Another wire 26 leads from the other terminal of the bell 2 to the main feed wire 22. The circuit through the bell will 75 thus be closed when the plunger 13 of the switch box F is moved downwardly into engagement with the contact 17. A train approaching the crossing from the right hand side would operate the switch in this 80 manner and cause the bell 2 to be sounded. In Fig. 3 the plunger 13 is shown as locked in operative position by the detent 19. After the train has passed over the crossing it will engage the trip lever 5 of the opposite 85 switch box E and swing the same to move the plunger 12 thereof into engagement with the contact 16. A wire 27 leads from the feed wire 23 to the said plunger 12, while a wire 28 leads from the said contact 16 to one 90 of the terminals of the electro-magnet 20 of the switch box F, the other terminal of the said electro-magnet being connected by a wire 29 to the wire 26 through which it communicates with the other feed wire 22. The 95 operation of the plunger 12 of the switch box E thus closes the circuit of the magnet 20 of the switch box F and causes the detent 19 to be swung back into inoperative position. The plunger 13 of the switch box 100 F is thus released and moved upwardly into its original position by the action of the spring 15, thereby opening the circuit of the bell and stopping the ringing of the bell.

A train approaching the crossing from 105 the left hand side will engage the trip lever 5 of the switch box E and cause the same to move the plunger 13 of the said switch box into operative position, whereupon the plunger will be engaged by the detents 110 19 and locked in operative position. A wire 30 leads from the plunger 13 of the switch box E to the end of the wire 27, which in turn leads to the main feed wire 23. The contact 17 of the switch box E is connected 115 to a wire 31 which leads to the wire 25, said wire leading to one of the terminals of the bell 2. The return circuit from the bell 2 is completed through the wire 26. The bell thus continues to ring as long as the plunger 120 13 of the switch box E is held in operative position.

After the train has passed over the crossing it engages the trip lever 5 of the switch box F and swings the same to actuate the 125 plunger 12 of the said switch box. This plunger is connected by a wire 32 to the wire 27 which leads to the main feed wire 23. The contact 16 of this plunger 12 is connected to a wire 33 which leads to one of the 130

5 terminals of the electro-magnet 20 of the switch box E, the other terminal of the electro-magnet being connected by a wire 34 to the wire 26 which leads back to the other 10 main feed wire 23. The actuation of the plunger 12 of the switch box F will thus energize the electro-magnet 20 of the switch box E and swing the detent 19 of the switch box E into inoperative position, thereby releasing the plunger 13 of the switch box E 15 and permitting the same to be moved upwardly into its original position by the spring 15. The bell circuit is thus broken and the parts are all returned to their original 20 positions so that the signal can be operated by another train approaching the crossing from either direction.

Having thus described the invention, what I claim as new and desire to secure by Letters Patent, is:

1. A railroad crossing signal including switch boxes adapted to be mounted upon the track on opposite sides of the crossing, an electric signal for the crossing, an upright 25 trip lever mounted within each switch box and projecting into the path of the rolling stock so as to be swung in either direction according to the direction in which the rolling stock is moving, an electric switch 30 mounted within each box and arranged to be closed by the movement of the trip lever in one direction, circuits including the said switches and the electric signal, detents for locking the said switches in a closed position, electro-magnets mounted adjacent to the detents, a second electric switch mounted within each box and arranged to be closed by the movement of the trip lever in the opposite direction, and electric circuits including 35 the said second switches of each box and the electro-magnet of the other box, whereby the detent of one box will be moved into inoperative position by the operation of the adjacent electro-magnet when the second 40 switch of the other box is closed.

2. A railroad crossing signal including switch boxes adapted to be mounted upon the track on opposite sides of the crossing, an electric signal at the crossing, an upright 45 trip lever mounted within each box and projecting into the path of the rolling stock so as to be swung in either direction according to the direction in which the rolling stock is moving, lateral arms projecting in opposite directions from each trip lever, a 50 plunger slidably mounted within each switch box on each side of the trip lever, one of the plungers being adapted to be actuated by the corresponding lateral arm of the trip lever when the trip lever is moved in either direction, electric circuits including 55 the signal and controlled selectively by

one of the plungers of each of the boxes, means for holding the said plungers in operative position, and means actuated by the 65 opposite plunger of each box for releasing the first mentioned plunger of the other box.

3. A railroad crossing signal including switch boxes adapted to be mounted upon the track on opposite sides of the crossing, an electric signal at the crossing, an upright 70 trip lever mounted within each box and projecting into the path of the rolling stock so as to be swung in either direction according to the direction in which the rolling stock is moving, lateral arms projecting in opposite directions from each trip lever, a pair of spring actuated plungers mounted within each switch box and arranged in the path of the respective lateral arms so that 75 one of the spring plungers will be operated when the trip lever is moved in either direction, electric circuits including the electric signal and controlled respectively by one of the spring plungers of each of the boxes, 80 detents for locking the said spring plungers in operative position, electro-magnets for releasing the detents, and electric circuits including the said electro-magnets and controlled by the other plungers whereby 85 the detent of one box will be automatically released by the actuation of the second mentioned plunger in the other box.

4. A railroad crossing signal including switch boxes adapted to be mounted upon the track on opposite sides of the crossing, a signal at the crossing, an upright trip 90 lever mounted within each switch box and arranged with the upper end thereof projecting into the path of the rolling stock, an intermediate portion of the trip lever being provided with a ball while the lower end thereof is weighted to normally hold the trip lever in an upright position, upwardly converging walls projecting from the bottom of 95 each switch box and having spaced upper edges which are correspondingly notched to provide a socket for the reception of the ball of the trip lever, the trip levers being thus free to move in either direction according 100 to the direction in which the rolling stock is moving, means actuated by each trip lever when moved in one direction to put the signal in operation, and means actuated by each trip lever when moved in the opposite direction to stop the operation of the signal.

In testimony whereof I have signed my name to this specification in the presence of two subscribing witnesses.

CARL W. F. STROBEL.
